UNITED STATES PATENT OFFICE.

CHARLES R. BEALL, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 4, 1926. Serial No. 126,970.

My invention relates to railway traffic controlling apparatus, and particularly to apparatus of the type wherein train carried governing mechanism is controlled by energy received from the trackway. More particularly my present invention relates to the trackway portion of such apparatus.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway along which traffic normally moves in the direction indicated by the arrow. These rails are divided by insulated joints 2 into a plurality of track sections, of which only one section A—B is shown in the drawing.

Located adjacent the exit end of the section A—B are two sources of current differing in frequency. As here shown, these sources are a transformer C⁶⁰ and a transformer C¹⁰⁰, the primaries of which are connected with alternating current generators not shown in the drawing. The frequencies of the currents delivered by these transformers may, for example, be 60 cycles per second and 100 cycles per second, respectively, although I do not wish to limit myself to these particular frequencies.

The section A—B is provided with a track circuit which is normally supplied with 60 cycle current from the transformer C⁶⁰, the secondary circuit for this transformer including the primary 12 of a track transformer T and the back contact 9—9^b of a coding device D hereinafter explained. The secondary 13 of transformer T is constantly connected across the rails of section A—B through a limiting impedance 3. Located at the entrance end A of the section A—B is a track relay R having two windings 4 and 5, winding 4 being constantly connected with the track rails 1 and 1^a of section A—B. This relay is of a type requiring alternating currents of the same frequency in its two windings 4 and 5 to effectively energize the relay, and as here shown, the relay is of the centrifugal type comprising a rotor 6 operated by the windings 4 and 5 and a back contact 7 which is open only when the cen-

trifugal device 14 is rotating at or above a 55 predetermined speed. Winding 5 is energized from the secondary of a transformer E, the primary of which is normally supplied with 60 cycle current from the secondary of transformer C⁶⁰ through back contact 60 9—9^b of the coding device D. It will be seen, therefore, that under normal conditions, that is, when the track section A—B is unoccupied, 60 cycle current is supplied to both windings 4 and 5 of relay R and so 65 this relay is effectively energized to hold its back contact 7 open.

The coding device D comprises a winding 15 provided with a circuit which passes from terminal 10 of a suitable source of current 70 through a back contact 8 controlled by winding 15, then through winding 15 and back contact 7 of relay R to terminal 11 of the same source of current. It follows that when back contact 7 is closed, the device D 75 will be alternately energized and de-energized due to the fact that its own back contact 8 is included in the circuit of the operating winding 15, and so the second contact 9 of this device will alternately engage contact points 9^a and 9^b. When contact 9—9^a of the coding device D is closed, the supply of 80 60 cycle current from the transformer C⁶⁰ to the track rails is discontinued, and 100 cycle current from the transformer C¹⁰⁰ is 85 then supplied to the rails, the secondary circuit for transformer C¹⁰⁰ including contact 9—9^a and the primary 12 of the track transformer T. It follows that when a train occupies section A—B, so that the back contact 90 7 of track relay R is closed, the rails of this section are alternately supplied with 60 cycle current and with 100 cycle current. The apparatus is intended for co-operation 95 with train-carried governing mechanism which responds to the intermittent supply of 100 cycle current but not to the continuous supply of such current or to 60 cycle current.

I have found that the centrifugal relay R 100 will not become effectively energized when its winding 5 is supplied with 60 cycle current alone and its track winding 4 is alternately supplied with 60 cycle current and 105 100 cycle current, and so if winding 5 were merely supplied with 60 cycle current the relay would not become energized when a train leaves section A—B. Furthermore, I

have found that this relay will not become effectively energized if 60 cycle current and 100 cycle current are simultaneously supplied to the winding 5 and if these currents are alternately supplied to the winding 4. I have accordingly provided means for always supplying winding 5 with current of the same frequency as that supplied to the winding 4 through the track rails, and as here shown, this is accomplished by always supplying the primary transformer E with current of the same frequency as that supplied to the primary 12 of the track transformer T. That is to say, when contact 9-9^b of the coding device D is closed, 60 cycle current is supplied to the primaries of transformers E and T; whereas when contact 9-9^a is closed, 100 cycle current is supplied to the primaries of both transformers E and T.

When a train enters section A-B, it de-energizes relay R so that the coding device D is set into operation to alternately supply 100 cycle and 60 cycle current to the rails of section A-B. When the train leaves the section, the alternate supply of these currents continues until the centrifugal device 14 of relay R is brought up to a speed high enough to open contact 7. The coding device D then stops operating and so will supply 60 cycle current continuously to both windings 4 and 5 of relay R, so that this relay then operates in the usual manner.

Ordinarily the coding device D will be controlled in part by traffic conditions in advance of section A-B as well as by back contact 7 of relay R, but since this further control forms no part of my invention I have omitted it from the drawing in order to simplify the disclosure.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a relay having two windings one of which is energized from the track rails of said section, two sources of alternating current differing in frequency, means for constantly supplying current to the rails of said section from one of said sources when said

relay is energized and for supplying current alternately from said sources when the relay is de-energized, and means for always supplying current to the other winding of said relay from the source which is supplying current to the track rails.

2. In combination, a section of railway track, a relay having two windings one of which is energized from the track rails of said section, two sources of alternating current differing in frequency, a coding device controlled by said relay in such manner that the device is at rest when the relay is energized and in operation when the relay is de-energized, means controlled by said coding device when in operation for alternately connecting said two sources with the rails of the section, said device when at rest connecting one of said sources constantly with the track rails, and means for always supplying current to the other winding of said relay from the source which is supplying current to the track rails.

3. In combination, a section of railway track; a relay having two windings one of which is energized from the rails of said section, a centrifugal device actuated by currents in said windings, and a contact controlled by said centrifugal device; two sources of alternating current differing in frequency, means for constantly supplying current to the rails of said section from one of said sources when said relay is energized and for supplying current alternately from said sources when the relay is de-energized, and means for always supplying current to the other winding of said relay from the source which is supplying current to the track rails.

4. In combination, a section of railway track, a relay having two windings one of which is energized from the track rails of said section, two sources of alternating current differing in frequency, means for constantly supplying current to the rails of said section from one of said sources when the section is unoccupied and for supplying current alternately from said sources to the rails when the section is occupied, and means for always supplying current to the other winding of said relay from the source which is supplying current to the track rails.

In testimony whereof I affix my signature.

CHARLES R. BEALL.
